CARLTON N. OGDEN, OF HOUSTON, TEXAS.

LIQUID-VENDING MACHINE.

1,218,888.

Specification of Letters Patent.

Patented Mar. 13, 1917.

Application filed May 9, 1916. Serial No. 96,316.

To all whom it may concern:

Be it known that I, CARLTON N. OGDEN, a citizen of the United States, residing at Houston, in the county of Harris and State 5 of Texas, have invented certain new and useful Improvements in Liquid-Vending Machines, of which the following is a specification.

This invention relates to new and useful 10 improvements in a liquid vending machine.

The object of the invention is to provide a machine of the character described for the purpose of dispensing liquid drinks and embodies a mechanism provided to receive a 15 coin and which will deliver a quantity of liquid corresponding to the denomination of the coin deposited.

With the above and other objects in view the invention has particular relation to certain 20 novel features of construction, operation and arrangement of parts, an example of which is given in this specification and illustrated in the accompanying drawings, wherein—

25 Figure 1 is a perspective view of the machine,

Fig. 2 is a transverse sectional view thereof taken on the line 2—2 of Fig. 1,

Fig. 3 is a vertical sectional view thereof 30 taken on the line 3—3 of Fig. 1,

Fig. 4 is a horizontal sectional view,

Figs. 5 and 6 are fragmentary sectional views of the actuating mechanism and

Fig. 7 is the side view of the fluid container 35 and valve actuating mechanism.

Referring now more particularly to the drawings, the numeral 1 indicates the cabinet inclosing the operative mechanism. This cabinet is divided into upper and lower compartments by means of the transverse partition 2. This partition supports a circular platform 3 whereon is mounted a rotatable drum 4, interposed between which and the platform are suitable anti-friction bearings.

40 The drum 4 is fixed to a vertical shaft 5, whose lower end has a pinion 6 fixed thereto which is in mesh with a corresponding pinion 7, fixed upon the inner end of the transverse shaft 8. The outer end of this last

45 mentioned shaft has a crank 9 through which it may be turned and also has a pointer 10, to indicate the relative position of the drum 4. This drum is separated into a number of compartments which contain 50 different kinds of syrup, forming one of the ingredients of the drink and each compart-

ment is equipped with a pump as 11, of the ordinary and well known construction, each pump having a push rod 12 and a discharge spout 13. By manipulating the former 60 downwardly, the syrup is forced out through the corresponding discharge spout 13 into the glass 14, arranged underneath said spout.

In the lower compartment of the cabinet is the tank 15, containing crushed ice and 65 the pressure tank 16 containing carbonated water. Leading from this last mentioned tank is the pipe 17, which is formed into a coil in the tank 15 and leads up through the partition 2 and carries the container 18, 70 which is of a capacity to contain sufficient fluid that, when mixed with the syrup, will fill the glass 14. This container has a discharge spout 19 whose free end terminates below the container 18 and is arranged to 75 also discharge in the glass 14 simultaneously with the discharge of the syrup therein so that the syrup and water will be thoroughly mixed in the glass. Controlling the pipe 17, immediately underneath the container 18, is the valve 20 and controlling the discharge spout 19 above said container is the valve 21. These valves are manipulated through a suitable mechanism as 22, so that when the former is open the latter will be 80 closed and vice versa. There is sufficient pressure in the tank 18 to start the flow of fluid when the valve 20 is closed and valve 21 opened and when the flow is once started the spout 19 assisted by the pressure, will 85 act as a siphon to empty the container.

Rotatably mounted in suitable bearings in the sides of the cabinet is the transverse shaft 23 and fixed thereto are two laterally extending arms 24 and 25, the free end of 95 the former of which is enlarged and alined over the path of the push rods 12 and free end of the latter of which is pivoted to the mechanism 22 to operate said valves. The shaft 23 also has an arm 26 fixed thereto 100 whose free end is enlarged and turned at a right angle to the arm forming the platform 27, which has the vertical slot 28 therethrough. A coin chute 29 is provided which is secured to one side of the cabinet and 105 whose outer end has a slot to receive the coin. This chute declines inwardly and its inner end depends over the platform 27, said platform receiving the coin therefrom. Cut through the side of the cabinet underneath 110 the coin chute is a vertical slot 30 and extending through this slot is a rod 31, whose

2

outer end is formed into a handle 32. This rod is seated upon a coil spring 33 and is thereby held in elevated position above the platform 27. When the same is pulled 5 downwardly, its inner end will pass through the slot 28, without affecting the mechanism of the machine. If a coin is deposited it will pass through the chute 29 and on to the platform 27 and close said slot 28. When the 10 handle 32 is then pulled downwardly the inner end of the rod 31 will engage against the coin and cause the arm 26 to swing around into the position shown in dotted lines in Fig. 6, said rod gradually moving toward 15 the edge of the platform and finally passing by the same, as illustrated in Fig. 6. During this movement the rod will displace the coin from the platform and it will drop into a suitable coin receptacle (not shown). As 20 the arm 26 is forced around, the shaft 23 will be caused to turn, operating through the arm 25 to close the valve 20 and open the valve 21 and the liquid which has been held under pressure in the container 18, will es- 25 cape through the discharge spout 19 into the glass 14. At the same time the free end of the arm 24 will force the push rod 12, alined thereunder, downwardly, forcing a quantity of syrup through the corresponding dis- 30 charge spout 13 into the glass. When the handle 32 is released, it will be elevated by the spring 33 to its original position and the arms 24, 25 and 26 will also be elevated through the pull springs 34, 34, which are 35 attached to the respective arms 24 and 26 at one end and to the upper part of the cabinet at their other. The front part of the cabinet is provided with a dial corresponding to the different compartments of the drum 4 and 40 the crank may be turned, bringing the pointer to any desired indicating character on the dial, which will indicate that the discharge spout of the corresponding compartment of the drum 4 is alined over the glass 45 14 and arranged to discharge therein. The front part of the cabinet is provided with a container 35 having a covering with a trap door 36. This container is provided to receive drinking cups which are discarded as 50 soon as used as well as to receive the waste fluid which is discharged therein through the overflow pipe 37.

What I claim is:

1. A device of the character described in- 55 cluding a container, an inlet pipe leading thereto and a discharge pipe leading therefrom, a valve controlling each of said pipes, a valve actuating mechanism arranged to open one of said valves and simultaneously 60 close the other, in combination with a ro-

tatable drum separated into compartments provided to contain liquids and means for discharging said liquids from said respective compartments, said container and said compartments discharging at a common point. 65

2. A device of the character described in- 70 cluding a container, a discharge spout leading therefrom, a valve controlling said spout, a rotatable drum formed into separate compartments, for containing liquids, a pump for each compartment provided to force the liquid contained therein therefrom and a manual mechanism arranged to open said valve and to simultaneously manipulate 75 the corresponding pump.

3. In a device of the character described, a container having a plurality of compartments fixed relative to each other, said container being bodily rotatable, a mechanism carried by each compartment for discharging the contents thereof therefrom, means for actuating said mechanism, and a container having a discharge pipe, said container and said compartments discharging 80 at a common point. 85

4. In a device of the character described, a drum having a plurality of compartments, a mechanism carried by each compartment for discharging fluid therefrom, means for manually actuating said mechanism, means for 90 rotating said drum, a container, and inlet and outlet valves therefor in operative connection with and controlled by said actuating mechanism.

5. A device of the character described in- 95 cluding a container, an inlet pipe leading thereto and a discharge pipe leading therefrom, a valve controlling each of said pipes, a valve actuating mechanism arranged to open one of said valves and simultaneously 100 close the other, a rotatable drum formed into separate compartments for containing liquids, a pump for each compartment provided to force the liquid contained therein therefrom, a transverse shaft, a pair of arms 105 fixed thereto, one of which is in operative connection with the valve actuating mechanism and the other of which is arranged to manipulate said pump, said arms manipu- 110 lating said valve and pump simultaneously and operating to discharge the contents of said container and said compartments at a common point.

In testimony whereof I have signed my name to this specification in the presence of 115 two subscribing witnesses.
